UNITED STATES PATENT OFFICE.

FRED SQUIRE, OF WELLINGTON, KANSAS.

WIRE-LINE SPOOLER.

Application filed December 20, 1922. Serial No. 607,972.

To all whom it may concern:

Be it known that I, FRED SQUIRE, a citizen of the United States, residing at Wellington, in the county of Sumner and State 5 of Kansas, have invented new and useful Improvements in Wire-Line Spoolers, of which the following is a specification.

My invention relates to spoolers and more particularly to wire line spoolers specially 10 adapted for use in connection with the drilling of oil and gas wells.

The primary object of the invention is to provide a spooling mechanism by means of which the wire line may be readily 15 wound on the spool after the drilling operations are completed.

A further object of the invention resides in providing a support for the spool having means to raise and lower the spool and 20 adjust it on an even plane, to insure uniform winding of the line.

Another object of the invention is to provide a support having spaced standards which are adjustable with relation to each 25 other, to provide for the accommodation of spools of different sizes.

Other objects and advantages of the invention will be apparent during the course of the following description.

30 In the accompanying drawings forming a part of this specification and in which like numerals are employed to designate like parts throughout the same,

Figure 1, is a side elevation of the spooler showing the parts set-up for operation,

Figure 2, is a plan view of the structure with the spool removed,

Figure 3, is an end elevation of the same,

Figure 4, is a detail front view of the 40 guide member,

Figure 5, is a section on line 5—5 of Fig. 3, and

Figure 6, is a fragmentary detail perspective view of one cross bar of the bearing 45 support.

In the drawings, wherein for the purpose of illustration I have shown a preferred embodiment of my invention, the numeral 5 denotes generally a support including longitudinal ground bars 6 and 7 connected at their ends to the lower corners of the end members or standards 8, by means of bolts 9. The bars 6 and 7 are provided at one end with a series of openings 10, to 55 permit adjustment of the standards 8 to accommodate spools of various sizes.

Each standard 8 comprises a pair of spaced angle iron frames 11, of square configuration, with the channel of the irons directed outwardly. These frames are braced 60 in the corners by angle plates 12, and the upper corners of the frames are joined by cross bars 13.

A raising and lowering mechanism is provided at each end and being identically the 65 same it is thought the description of one mechanism will suffice. Reference to Figs. 3 and 5 will show that a pair of angle bars 14, extend horizontally across the frames 11, having slots 15 in their ends, as shown 70 more clearly in Fig. 6, to slidably engage the vertical flanges 16, of the frames 11. These bars are bridged by plate 17, at the center, which supports sectional bearings 18. Wood blocks 19 are seated in the channels 75 of the cross bars 14, being held in position by plate 20 carried by the head of screw jack 21 positioned intermediate the frames. These parts are connected by bolts 22 and 23 to form a rigid construction. Thus, it 80 will be seen that manipulation of the jack 21 will raise and lower the cross bars 14, which may be held in a fixed position by passing bolts 24, through the ends of the cross bars and the flanges 16. Each end is 85 adjustable independently of the other to serve the purpose of leveling the spool shaft if it is found to be uneven after being raised to the desired height.

Spool shaft 25 is disposed longitudinally 90 of the support, the ends of the shaft extending through the bearings 18. The spool 26 is revolvably mounted on the shaft 25 by means of the bushings 27 secured in each end. One end of the spool is joined to pulley 28, also revolvably mounted on the shaft, by means of flange 29 and revolves therewith. End movement of the spool is prevented by collar 30 mounted on the shaft adjacent the opposite end of the spool, being secured by 100 set screw 30'. The pulley 28 is rotated by belt 31 which is trained over a drive pulley attached to an engine, not shown.

The winding of the wire line is guided by the guide member 32, slidably mounted on cross rod 33, having depending supports 34 at each end, extending through eye bolts 35 projecting from the standards 8. This guide member is provided with a pair of pulleys 36 journaled in superposed relation 105 between spaced bearing plates 37, connected at their lower ends by bolt 38, as more

clearly shown in Fig. 4. External bosses 39 are cast integral with the plates 37 at the point where the cross rod 33 passes therethrough providing bearings for the guide member. For the purpose of anchoring the support to the ground, U-bolts 41 are fulcrumed adjacent the upper ends of the standards 8 between the frames 11 on each side. Chains or other fastening means 10 tend from these to the ground.

In operation the support is anchored to the ground adjacent the well being drilled. The spool is disposed between the standards and connected to the flange 29 formed integral with the pulley 28. Shaft 25 is passed through the pulley and spool and mounted in bearings 18. The spool is then elevated to the desired height by the raising and lowering mechanism. The winding of the 20 wire line on the spool is accomplished by engine power transmitted to the pulley 28 through the medium of belt 31. The guide member serves the purpose of uniformly winding the line on the spool. Thus, it will be seen that the wire line may be rewound by this machine in less time than it ordinarily requires other machines to do the same work.

It is to be understood that the form of 30 my invention herewith shown and described is to be taken as a preferred example of the same, and that certain changes in the shape, size, and arrangement of parts may be resorted to without departing from the spirit 35 of the invention or the scope of the subjoined claims.

Having thus fully described my invention, I claim:—

1. In a device of the character described, 40 a support comprising a pair of standards, each standard being composed of a pair of spaced open frames, cross bars slidably

mounted within the frames, bearing blocks carried by said cross bars, a shaft revolvably mounted in said bearing blocks, and means 45 for elevating said cross bars.

2. In a wire line spooler, the combination of a support having standards, each standard composed of a pair of spaced frames having inwardly directed flanges, movable 50 cross bars having end slots engaged by the flanges on said frames, bearing blocks carried by said cross bars, a shaft revolvably mounted in said bearing blocks, and means positioned beneath said cross bars for elevating said shaft.

3. In a wire line spooler, the combination of a support having standards, each standard composed of a pair of spaced frames having inwardly directed flanges, a pair of 60 L-shaped cross bars having end slots engaged by said flanges, a plate connecting said cross bars, bearing blocks carried by said plates, a shaft mounted in said bearing blocks, a removable cross rod mounted forwardly of said standards, and a guide movable transversely on said cross rod.

4. In a wire line spooler, the combination of a support including longitudinal ground bars, standards joined to each end of said 70 ground bars, each standard composed of a pair of spaced rectangular frames, horizontal bars extending across said frames having sliding connection therewith, raising and lowering means positioned beneath said horizontal bars, bearing blocks supported by said horizontal bars and a spool shaft journaled in said bearings.

In testimony whereof I affix my signature in the presence of two witnesses.

FRED SQUIRE.
